UNITED STATES PATENT OFFICE.

FRANK J. SCHLUETER AND MANUEL LOZANO, OF HOUSTON, TEXAS; SAID LOZANO AS SIGNOR OF ONE-FIFTH OF HIS RIGHT TO SAID SCHLUETER.

GUARD FOR RAILWAY CROSSINGS.

Application filed October 23, 1922. Serial No. 596,477.

To all whom it may concern:

Be it known that we, FRANK J. SCHLUETER and MANUEL LOZANO, citizens of the United States, residing at Houston, in the county of Harris and State of Texas, have invented certain new and useful Improvements in Guards for Railway Crossings, of which the following is a specification.

This invention relates to new and useful improvements in a guard for railway crossings.

One object of the invention is to provide a guard adapted to be placed at the crossing of a roadway and a railway and designed to automatically block the roadway, by means of suitable gates or guards, when a train is approaching the crossing.

Another object of the invention is to provide a device of the character described which not only blocks the roadway on each side of the railway track but which also serves as a signal to warn travelers on the roadway of the near approach of a train toward the crossing.

With the above and other objects in view the invention has particular relation to certain novel features of construction, operation and arrangement of parts, an example of which is given in this specification and illustrated in the accompanying drawing, wherein:—

Figure 1 shows a plan view of the device.

Figure 2 shows an enlarged fragmentary side elevation thereof.

Figure 3 shows an enlarged fragmentary perspective view.

Figure 4 shows a side elevation of the signal device employed.

Figure 5 shows a partial plan view thereof and

Figure 6 shows an enlarged plan view of a guard arm.

In the drawings the numeral 1 designates the railway track as a whole which is crossed by the ordinary roadway 2 for vehicles and pedestrians. On opposite sides of the roadway 2 there are the rotatable shafts 3, 3, which have bearings in the posts 3' located on opposite sides of the track. Arranged on opposite sides of the railway track are the gates or guards 4, 4 which are pivoted to the respective side posts 4', 4', as shown. One end of these guards is designed to project across the roadway, and their other ends carry the weights 5, 5 which normally hold the

guards in elevated position to permit passage along the roadway 2.

On opposite sides of the crossing and located at a suitable distance therefrom are the levers 6, 6 which are arranged on suitable cross ties and pivoted thereto at their centers. The corresponding ends of these levers are connected by wire cables 7, 7. Each shaft 3 has an upstanding arm 8 to which the respective cables are attached. There is a lift arm 9 slidable in vertical aligned bearings carried by each post 3'. The upper end of this arm is curved and attached to said curved end there is a cable 10 which passes through a long slot 36 in the arm 37 carried by the weighted end of the guard 4, and the lower end of the cable 10 carries said weight 5. Each shaft 3 also has an arm 11 fixed thereto whose free end is connected to the lower end of the arm 9 through the link 12. When the corresponding cable 7 is moved in one direction it will operate through the arms 8 and 11 to actuate the link 12 which in turn will lift the arm 9, and this arm will operate through the cable 10 to lift the weight 5 and as said cable 10 moves upwardly it will release the nut 38 fixed to said cable, from the arm 37 of the guard 4, allowing the guard to move into horizontal position across the roadway 2, by gravity. When the cable 7 is released the guard 4 will assume an elevated position through the influence of the weight 5. This guard 4 may be colored so as to readily attract attention, and if desired there may be suspended from it the pendants 13 with wire mesh as 14 to form a better protection for the crossing.

For operating the levers 6 we have provided a mechanism which will now be described. Outside of each lever there is rotatably mounted in suitable bearings on the railway tie, a shaft 15 having the upstanding arm 16 which is normally held in vertical position by means of pressure springs 17, 17 which act against opposite sides of a plate 18 which is fixed to and upstands from the shaft 15. There is a rod 19 which is slidable through a bearing in the adjacent end of the lever 6 and this rod has the fixed collars 20 and 21 spaced apart thereon. One end of this rod is connected to the arm 16 through a link 22. Adjacent the railway rail, on the inside, there is an upstanding lug 23 which is fixed to the shaft 15 and whose upper

end has an enlarged head 24 provided with a groove to receive the flange of the wheels of the locomotive. When the locomotive is approaching a crossing the wheels will depress said lug, moving it toward the crossing thus partially rotating the shaft 15. This movement will act through the arm 16 and the link 22 to move the collar 20 of the rod 19 against the corresponding end of the lever 6 and said lever will operate to exert a pull on the cable 7 attached to the other end thereof, and this pull will operate not only to partially rotate the shaft 3, to which said cable is connected, but will also operate to actuate the lever 6 at the opposite side of the crossing which in turn will exert a pull on the other cable 7 resulting in a partial rotation of the other shaft 3. These operations will occur practically simultaneously and the partial rotations of the shafts 3 will operate through the mechanism described to lift the weights 5 and permit said guards to fall horizontally across the roadway 2. The lug 23 will be depressed successively by the wheels of the train operating thereover, but the rod 19 will move idly and the arms 11, the link 12 and the arm 9 being in straight alignment will hold the weight 5 elevated until the train has passed the crossing. As the train is leaving the crossing its wheels will of course depress the lug 23 on the opposite side of the crossing in the reverse direction, that is away from said crossing. This will operate through the mechanism described, to move the rod 19 in the reverse direction, and the collar 21 will engage with the lever 6 and reverse the position of both levers, through the cables 7, partially rotating the shafts 3 to swing the arms 11 around and permit the weight 5 to descend. The nuts 38 will then engage the arms 37 and carry the guards 4 into vertical position.

A warning signal is also provided, preferably one on each side of the crossing.

The construction and operation of this signal will now be described:—One end of the shaft 3 has a pinion 25 fixed thereon, in mesh with a similar pinion 26 fixed on the lower side of the circular platform 27. This platform is rotatable on a suitable stand 28 and has an arcuate slot 29 cut therethrough. The shaft 3 has an upstanding fixed arm 30 which works through said slot and mounted on the platform 27 there is a manikin 31 to which a lever 32 is pivoted. There is a link 33 connecting the upper end of the arm 30 with one end of the arm 32 and the other end of this arm carries a disc like stop signal 34, and at night the manikin may also carry a lantern 35 if desired.

The signals are operated through similar mechanism, so only one has been described.

As the shafts 3 are rocked back and forth the platform 27 will also turn back and

forth and the signals 34 will be moved up and down to attract the attention of those approaching the crossing and warn them of the approaching train.

What we claim is:—

1. A device of the character described including a pivotally mounted road guard arranged alongside the railway track, means normally holding said guard in approximately vertical position, a mechanism connected to said means through which the same may be released to permit said guard to swing into approximately horizontal position, said mechanism including a member arranged in position to be actuated by the truck wheels passing along said track, and to thereby release said means to permit said guard to swing into said horizontal position, and a signal device in operative connection with and actuated by said mechanism. 70 75 80 85

2. A device of the character described including a pair of pivotally mounted road guards mounted on opposite sides of a railway track, means normally holding said guards in vertical position, a common mechanism operatively connected with said means and arranged to be actuated by the wheels of the trucks and passing along said track to permit said guards to swing into horizontal position, and a signal device arranged on each side of said track and operatively connected with said mechanism and operated thereby simultaneously with the operation of said guards. 90 95 100

3. A device of the character described including a pivotally mounted road guard arranged alongside a railway track, a weight connected to said guard and normally operating to hold the same in vertical position, a mechanism connected to said weight and formed with a lug alongside the railway rail and adapted to be actuated by the truck wheels and to thereby operate said mechanism to lift said weight and permit said guard to swing into horizontal position by gravity. 105 110

4. A device of the character described including a pivotally mounted road guard arranged alongside a railway track, a weight connected to said guard and adapted to hold the same in vertical position, a mechanism connected to said weight and including lugs spaced apart and arranged alongside the railway rails, said lugs being arranged to be actuated by the truck wheels passing over said track successively, the actuation of one lug toward the other operating through said mechanism to lift said weight and permit said guard to swing into horizontal position, and the successive actuation of the other lug in the reverse direction operating to release said weight whereby the same operates to swing said guard into vertical position. 115 120 125 130

5. A device of the character described, including a pivotally mounted road guard arranged alongside a railway track, means normally operating to hold said guard in elevated position, a mechanism connected to the guard and arranged to be actuated by the truck wheel to swing said guard into approximately horizontal position and a signal device operatively connected with and actuated by said mechanism, said signal device being mounted to rotate on a vertical axis, and including an oscillating member connected to, and actuated by said mechanism.
- 10 6. A device of the character described, including a pivotally mounted road-guard, arranged alongside a railway track, means

connected to said guard, and normally operating to hold the same in approximately vertical position, a mechanism connected to 20 said guard and formed with a lug alongside the railway rail, and adapted to be actuated by the truck wheels, and thereby operate said mechanism to neutralize the influence of said means and permit said guard to 25 swing into horizontal position by gravity.

In testimony whereof we have signed our names to this specification in the presence of two subscribing witnesses.
